UNITED STATES PATENT OFFICE.

WINFIELD S. CARTER, OF ASHTABULA, OHIO.

DESIGN FOR A CARPET-SWEEPER CASE.

SPECIFICATION forming part of Design No. 14,493, dated December 18, 1883.

Application filed October 13, 1883. Term of patent 14 years.

To all whom it may concern:

Be it known that I, WINFIELD S. CARTER, a citizen of the United States, residing at Ashtabula, in the county of Ashtabula and State of Ohio, have invented and produced a new and original Design for Cases for Carpet-Sweepers, of which the following is a specification, reference being had to the accompanying drawing, forming part thereof.

10 In the accompanying drawing the figure is a perspective view of my newly-designed case.

The top and bottom edges of the end pieces, D, of the casing are parallel with each other, and at about the center of said bottom edge is formed an arch, E. The ends of said pieces D, between the top and bottom edges, have the form of ogee curves, as shown. The sides of the casing are formed of the side pieces, C and B, which are curved transversely to conform to the curves of the end pieces, D. The upper edges of the pieces C meet the lower edges of the pieces B, and the upper edges of said

pieces B terminate flush with the top edge of the end pieces, D. The top A of the casing is a flat rectangular strip, the longitudinal edges 25 of which overhang the pieces B.

I claim—

1. The design for carpet-sweeper casings herein shown and described, consisting of a flat top, end pieces, the ends of which have the 30 form of ogee curves, and the sides transversely curved to correspond to the curves of the end pieces.

2. The design for carpet-sweeper casing herein shown and described, the same consisting of end pieces arched at the bottom and having ogee curves at each end, the transversely-curved lower side pieces, the transversely-curved upper side pieces, and the flat top. 35

WINFIELD S. CARTER.
